ATTORNEY

UNITED STATES PATENT OFFICE.

HENRY C. HUSEMANN, OF ST. LOUIS, MISSOURI.

DESIGN FOR A DEODORIZER.

49,741.

Specification for Design.

Patented Oct. 10, 1916.

Application filed July 26, 1916. Serial No. 111,540. Term of patent 7 years.

To all whom it may concern:

Be it known that I, HENRY C. HUSEMANN, a citizen of the United States, residing at St. Louis, in the county of St. Louis and State of Missouri, have invented a new, original, and ornamental Design for a Deodorizer, of which the following is a specification, reference being had to the accompanying drawing, forming part thereof.

Figure 1 is a front view, and Fig. 2 is a

side view of a deodorizer, showing my new design.

I claim:

The ornamental design for a deodorizer, as shown.

HENRY C. HUSEMANN.

Witnesses:

JOHN BERKEMEIER,
LOUIS HUSEMANN.
